UNITED STATES PATENT OFFICE

2,483,003

BIRD CAGE SWING

James J. Fischer, Milwaukee, Wis.

Application December 8, 1945, Serial No. 633,611

2 Claims. (Cl. 119—25)

1

This invention appertains to perches for bird cages.

One of the primary objects of my present invention is to provide a perch which will be pleasing and attractive to the eye, and at the same time afford a comfortable rest for the bird.

Another salient object of my invention is to provide a perch for canaries and other birds, embodying a ring formed from a plastic for sanitary and beauty reasons, and a novel stirrup block associated with the ring for permitting the bird to effectively grip the perch without undue strain on the muscles of the legs of the bird.

A further object of my invention is to provide novel means for associating a wooden or like perch grip with the lower end of the ring forming the body or main portion of the perch, said grip being of a greater thickness or diameter than the ring.

A further object of my invention is to provide a novel and economical means for closing the upper end of the ring and for connecting such upper end with a supporting member, so that the perch can be readily associated with a supporting hanger wire, or the like.

A still further important object of my invention is to provide a novel means for forming the hook or supporting member for the ring, whereby the same can be used as a trap for insects, such as mites.

With these and other objects in view, the invention consists in the novel construction, arrangement and formation of parts, as will be hereinafter more specifically described, claimed, and illustrated in the accompanying drawing, in which drawing:

Figure 1 is a front elevational view of my improved perch with parts thereof broken away and in section to illustrate structural detail, the perch being shown associated with a weighing scale.

Figure 2 is a vertical sectional view taken substantially on the line 2—2 of Figure 1, looking in the direction of the arrows.

Figure 3 is an enlarged detail sectional view taken on the line 3—3 of Figure 1, looking in the direction of the arrows.

Figure 4 is an enlarged fragmentary detail sectional view taken substantially on the line 4—4 of Figure 1, looking in the direction of the arrows, illustrating the novel means employed for connecting the upper end of the perch with a supporting hanger, or the like.

Figure 5 is a fragmentary detail side elevational view illustrating a modified form of hanger

2

bracket for the body of the perch, a part of the bracket being shown broken away and in section, the part in section being taken substantially on the line 5—5 of Figure 6, looking in the direction of the arrows, and

5 Figure 6, a sectional view showing the modified form of hanger bracket, the section being taken substantially on the line 6—6 of Figure 5, looking in the direction of the arrows.

10 Referring to the drawing in detail, wherein similar reference characters designate corresponding parts throughout the several views, the letter P generally indicates my bird perch, and the same includes a main body portion 10, preferably formed as a ring. This body portion 10 can be constructed from any desired material, but preferably from a suitable plastic. As illustrated, the ring can be in the nature of a tube and the tube is then curved into an annular 15 shape. The ends are slightly spaced, as at 11, for a purpose, which will be later set forth. If desired, the ring 10 can be made of solid material and in this instance, the terminals of the ring are bored to provide openings or sockets.

20 25 The ring 10 is associated with a hanger bracket 12 in a novel manner, whereby the perch can be readily suspended from any suitable support, such as a wire, or the like.

In Figures 1 to 4, inclusive, I have shown the 30 hanger bracket to be a weighing scale and the scale, per se, forms no part of my present invention. However, it is to be noted at this point, that the manner of associating the hanger bracket or scale 12 with the ring, does form an 35 essential part of my present invention.

Briefly, the weighing scale or hanger bracket 12 includes an upper cylinder 13, having formed on its upper end a bendable lip 14 which can be hooked over a wire, or the like, and the lip can 40 be bent down to form a hook to prevent the slipping of the cylinder off of such wire.

Slidably mounted within the cylinder 13, is a 45 folded piece 15, and the lower end of the cylinder, on its opposite sides, is provided with bent in tongues 16 which slide in guideways in the piece 15. A spring 17 is placed within the piece 15 and the lower end of the spring engages the tongues 16. The piece 15 has formed thereon, an upwardly extending indicating pointer 18, 50 which travels over graduations 19 on the outer face of the cylinder 13.

In accordance with my invention, the piece 15 has formed on its lower end, a depending arm 20, and the arm in turn has formed on its opposite 55 sides, oppositely and laterally extending legs 21.

The legs 21 are rolled or curved to provide barrels. These curved legs are inserted in the terminals of the ring 10, and if so desired, an adhesive can be used for securing the legs in the hollow portion of the ring. If the ring is solid and the ends are provided with sockets, then the legs are inserted in such sockets.

From the above description, it can be seen that the lower end of the hanger 12 is of a substantially inverted T shape.

In view of the fact that the ring 10 is comparatively thin in cross-section, I provide a novel saddle or stirrup block or perch grip 22 for the bird. This block is preferably, but not necessarily made of wood and is of a round shape in cross-section. The lower face of the block has formed therein a longitudinally extending groove 23 and the groove is of an arcuate shape in cross-section to conform to the transverse curvature of the ring 10. The ends of the block are cut away as at 24 so that the block will not protrude beyond the size of the ring, and the groove 23 extends up the ends of the block as at 25. Hence, the block or perch grip fits snugly on the ring. The block can be secured to the ring by a suitable adhesive. The block or grip effectively fills the lower end of the ring and the block lies in a substantially horizontal plane. The upper surface of this block can be serrated or roughened, if so desired. Obviously, this block allows a canary or other bird to obtain a firm foothold on the perch without undue muscle strain.

It is not essential to the present invention that the hanger 12 be in the nature of a weighing scale, and in Figures 5 and 6, I have shown another type of hanger bracket, and this bracket is generally indicated by the reference character 26.

The hanger bracket 26 is formed from a single sheet of metal and includes an upright arm 27. The upper end of the arm 27 is bent down to form a hook 28. The hook 28 is utilized for permitting the connection of the bracket with a wire or the like. Both the arm 27 and the hook 28 are preferably curved so as to form an inner receptacle 29, the purpose of which will be later described. The lower end of the arm 27 has formed thereon a depending inverted T shaped extension 30, and this T shaped extension 30 includes laterally extending legs 31, which are preferably rolled to provide barrels. The legs or barrels are inserted in the ring 10 in the same manner as the legs and barrels 21 in the first form of my invention.

The perch formed in accordance with my invention, is of a light but rugged construction, and can be economically made and will present a pleasing and attractive appearance to bird owners.

The receptacle 29 above mentioned provides a trap for small insects such as mites. In accordance with my invention, I place a small piece of absorbent material 32 in said receptacle. In practice, it has been found that the mites will leave the bird in the daytime and hide in crevices in the perch. Thus, with my invention, in the daytime when the mites leave the bird, a few drops of kerosene or any other preferred insecticide can be squirted on the absorbent material to kill the mites, after which the absorbent cotton can be removed and a new piece inserted.

Changes in details may be made without departing from the spirit or the scope of my invention, but what I claim as new is,

1. A perch for bird cages comprising a body of a substantially ring shape, a bracket carried by the upper end of the ring for connecting the same to a support, and a saddle block constituting a bird grip secured to the lower end of the ring and filling in the lower portion of the ring and lying substantially in a horizontal plane, said saddle block being of a greater thickness than the thickness of the material from which the ring is made, and having its lower face provided with an arcuate groove for snugly receiving the inner face of the ring, the wall of the groove extending to the top face of the block at the terminals thereof, whereby said top face will closely engage the inner face of the ring.

2. A perch for bird cages and the like, comprising a body having spaced ends provided with openings therein, a hanger support for the body, including an arm, a depending leg on said arm, forming a connection therewith a hook, said arm and leg being rolled toward one another and defining a receptacle, absorbent material removably fitted in the receptacle and a depending inverted T shaped head on said arm received in the openings in the body.

JAMES J. FISCHER.
